United States Patent Office

Des. 217,895
Patented June 30, 1970

217,895

FASTENER FOR WELT LOOP HOSE OR SIMILAR ARTICLE

Aaron Burleson, Burlington, N.C., assignor to Burlington Industries, Inc., Greensboro, N.C., a corporation of Delaware

Filed Nov. 22, 1968, Ser. No. 14,595

Term of patent 14 years

Int. Cl. D2—08

U.S. Cl. D2—409

Fig. 2.

Fig. 3.

Fig. 4.

Fig. 1.

FIG. 1 is a front elevational view of a fastener for welt loop hose, showing my new design, the side opposite being a mirror image thereof;

FIG. 2 is a bottom plan view of the fastener as shown in FIG. 1;

FIG. 3 is a side elevational view of the left side of the fastener as shown in FIG. 1; and

FIG. 4 is a side elevational view of the right side of the fastener as shown in FIG. 1.

I claim:

The ornamental design for a fastener for welt loop hose or similar article, as shown and described.
